MEANS FOR SPACING TURBINE BLADES
WHILE SECURING THE SAMELisle F. Small and Paul F. Lee, United States
Navy, and Arvah A. Jennings, Vallejo, Calif.Original application March 12, 1934, Serial No.
715,094. Divided and this application July 14,
1938, Serial No. 219,192

2 Claims. (Cl. 29—89)

(Granted under the act of March 3, 1883, as
amended April 30, 1928; 370 O. G. 757)

The subject matter hereof is division of our copending application Serial No. 715,094, filed March 12, 1934, Patent No. 2,128,268, dated Aug. 30, 1938, which is a continuation in part of our then copending application Serial No. 537,380, filed May 14, 1931, now Patent No. 1,953,089.

Our invention relates to apparatus for spacing and securing turbine blades to their lacing, and more particularly to the spacing of and rigid 10 securing for the unsecured ends of the blades or vanes of a turbine without occasioning enduring strains in the blades which may be transformed into harmful distortion of the blades by the heat and speed changes to which the turbine 15 may be subjected.

The object of our invention is to provide an improved apparatus whereby the unsecured ends of turbine blades may be readily and properly spaced apart and secured in convenient groups 20 to their lacing without liability to harmful distortion of the blades arising from such spacing and securing.

In the accompanying drawing illustrating the embodiment of our invention: Fig. 1 indicates 25 a top plan view of a portion of a row of turbine blades, which may be either rotor or stator, and our improved tool for spacing the blades the proper equal distance apart throughout the row.

Figs. 2 and 3 are opposite side views of the 30 tool shown in Fig. 1.

Fig. 4 is a front elevation view, partially in section, of a portion of a row of blades or vanes and the relation of the spacing tool thereto when employed in spacing the blades or vanes the 35 proper equal distance apart throughout the row.

Fig. 5 is a side elevation view of the tool we have devised for securing each blade or vane in a row to the lacing.

Fig. 5A is a perspective view of the jaws of 40 the clamping tool; and

Fig. 6 is a top plan view of the forward portion of the jaws of the tool shown in Fig. 5 relative to some of the blades or vanes to be secured to their lacing.

In steam turbine practice the blades or vanes are at times subject to wide changes in temperature, and in operation are subjected to high speeds. These exacting conditions render it highly desirable that each blade or vane be secured in place normally without strains. Strains in such blades or vanes we have found most productive of distortion, due to expansion and contraction action by the wide temperature changes. We have always found that such distortion as well as any unequal spacing of the blades or

vanes in each of their several rows tends to destroy the static as well as dynamic balance of the rotor, and may lead to interference between the juxtaposed alternate rows of rotor and stator blades or vanes, which interference may 5 result in very great damage to the turbine. These substantial problems are successfully, conveniently and economically solved by the means provided by our present invention.

In the drawing, in which like characters of 10 reference indicate the same parts, 10 represents, in the instance shown in Fig. 4, a portion of a turbine rotor in which the turbine blades or vanes extend radially outward therefrom. It is perfectly obvious to anyone skilled in the art 15 that the turbine stator units each form a circle having the turbine blades or vanes secured at their outer ends thereto and extending radially inward therefrom, and that our invention may be similarly applied to both rotor and stator 20 vanes or blades.

11 represents the typical turbine blades or vanes. A preferably round hole is punched or drilled through each blade near its free end, which free end is the outer end in the rotor 25 blades or vanes and the inner end in the stator blades or vanes. Through each of these holes is passed a preferably round rod or tube 14 of a length that will pass through the desired number of blades 11, which number of blades form 30 a group. The blades 11 of each group are uniformly spaced apart and are then secured in such position by flattening the rod or tube 14 intermediate each blade 11. This flattening of tube 14 provides a surface 15 of substantial area 35 between each blade 11 and in a plane substantially at right angles to the length of each blade 11 and serves the further purpose of tending to confine the greater portion of the motive fluid axially flowing through the turbine between the 40 blades 11 and the stator or rotor and the tubes 14 and thus tends to minimize the leakage of the motive fluid at the free ends of the blades. The tubes 14 provide adequate strength as well as lightness in weight and at the same time are 45 more readily flattened into broader surfaces 15 which serve the two-fold purpose of securing the properly spaced blades at their free ends and to reduce leakage of motive fluid at the free ends of the blades to an advantageous extent beyond 50 that of the normal member 14.

There are many blades or vanes in each rotor or stator unit of a turbine, as well as many such units in each turbine, which require many flattening of the tubes 14. To reduce the assembly 55

and replacement cost of turbines provided with our invention we have devised simple, readily operable, durable and inexpensive means for spacing and securing the normally free ends of each of the blades or vanes. Said means includes a securing tool which is provided with a preferably rectangular bar or body 20 having a portion 21 slidably mounted thereon. From one side and end of body 20 and portion 21 extend respectively 5 jaws 22 and 23, Figs. 5 and 6, whose outer ends are narrow and curved as shown, so that the juxtaposed surfaces of said jaws may extend into the space between the blades 11 in the region of tube 14. Projecting from the side of portion 21 10 preferably opposite its jaw 23 extends a handle member 24 rigidly attached to or integral with said portion 21. A handle member 25 is provided near one end with a plurality of bearing openings 26 extending therethrough, either one of which 15 being adapted to receive a pin 27 projecting from one side of body 20 near its upper or outer end. Said pin 27 may be integral with body 20 or independent thereof and insertable into an opening therein. Adjacent the openings 26 the handle member 25 is provided with a cam surface 28 juxtaposed to and adapted to engage the adjacent 20 surface of portion 21. A spring 29 connects handle member 25 and jaw 23 so that handle members 24 and 25 are normally held apart, and 25 moved a substantial distance toward each other when engaged by the hand, the outer portions of handle members 24 and 25 being shaped to conform to the hand grip. One of the handle members 24, 25 has a screw 30, or other adjustable 30 means, extending therethrough provided with a lock-nut 31 and whose end is adapted to contact with the other handle member for limiting the movement of said handle members and the distance apart of the juxtaposed surfaces of the jaws 35 22 and 23, which distance may be conformed to the distance desired between the flattened surfaces 15 of the tube 14. This distance may be varied to any desired extent by the adjustment of screw 30, and fixed by the setting of lock-nut 31.

45 When handle member 25 has one or the other of its bearing openings 26 occupied by pin 27 a different leverage is adapted to be exerted by its cam surface upon the sliding portion 21 and its jaw 23.

From preferably opposite sides of jaw 22 extends a pin 32 adapted to serve as a gauge against the sides of blades or vanes 11 and insuring substantial uniformity in the relative positioning of 50 jaws 22 and 23 and tube 14 between the blades 11, thus encouraging speedy manipulation of the jaws 22, 23 and the uniform efficiency of their results.

It will be understood that the tubes 14, of a 55 length to extend through the desired number of blades or vanes 11 are inserted into the opening, conforming to the size of tube 14 extending through each blade in its group, with a space indicated at 35 in Fig. 1 between the ends of tubes 60 14, so as to admit, without any impairment, the expansion of the tubes 14 under the high working temperatures prevailing in turbine practice. The screw 30 being adjusted to afford the desired extent to which the tube 14 may be flattened, the 65 jaws 22 and 23 are then inserted between the blades 11 to an extent determinable by the pins 32, said insertion not interfering with the spacing means or tool hereinafter described. The handle members 24 and 25 are then gripped until 70 screw 30 limits their further movement, which 75

correspondingly flattens the portion of tube 14 between the adjacent faces of jaws 22 and 23. Such flattening of tube 14 by jaws 22, 23 so inserted between a pair of blades 11 would normally spread such pair of blades further apart by the 5 resulting distortion of tube 14, but the portions 43, 44 of the hereafter described blade spacing and holding means, Figs. 1 and 4, engaging the outer surfaces of said pair of blades counteract the transitory strain on said blades occasioned 10 by said flattening and thus precludes such spreading apart of said pair of blades 11. This operation is repeated on the tube 14 between each blade 11. This upsets the metal of the tube 14 15 against each of the opposite surfaces of each blade 11 and substantially rivets the blades or vanes in their spaced positions due to the increased diameter, beyond that of each hole through each such blade, and which flattened diameter also tends to act as a shroud tending to 20 limit the escape of the motive fluid from the free ends of the blades or vanes.

Where the turbine blades or vanes are long, or temporary space blocks between all of the blades are undesirable preliminary to their being secured in their spaced positions, or where such securement is desired with lesser liability of lateral displacement strain upon the blades, the jaws 22 and 23 are bifurcated as shown in Fig. 6 25 to slip on opposite sides of a blade 11. Such 30 bifurcated jaws will simultaneously flatten only that portion of the tube 14 on opposite sides of the blade between the bifurcated jaws and will not disturb the diameter of the tube juxtaposed to surfaces of adjacent blades. It will be understood that the blades 11 that are each successively secured to the tube or lacing member 14 35 are the pair of blades 11 which are then being held in their proper spaced relation by the projection portions 43, 44, of the spacing and holding means hereinafter described. Such securement of blades 11 to tubes 14 will subject such portions 43, 44 to substantially less stress, due to the lesser tendency to crowd successively the blade 11 away from the portion of the tube being 40 flattened, as heretofore described, than when flattened on one side only of the blade, which latter tends to place undue strains upon the blades. The bifurcated jaws 22, 23 are preferably curved, as shown in Fig. 6, conformable to 45 the curvature of the blade or vane adapted to occupy the bifurcation.

In flattening each tube 14 without rupturing or unduly distorting the metal of the tube adjacent each surface of each blade 11, the opposite 55 sides of each jaw 22 and 23 is provided with a depression 36 adapted to be positioned upon opposite sides of the center of tube 14 to more progressively flatten such portion of the tube, substantially as indicated in Fig. 4.

Our invention also provides means for the uniform spacing of adjoining blades and holding them against displacement due to the stresses occasioned by and while they are being laced or secured in such position, as indicated in Figs. 60 1 to 4. The securing and the spacing-holding means are severally and jointly adapted not to interfere with each other in the efficient closeness of their operative positions in which the spacing-holding means neutralizes the normal 65 tendency to displace the blades by the stresses occasioned by the securing means, and which indicates the relationship and joint functioning of said means, which in the instance shown are several, in the attainment of their unitary result.

A pair of arms 40 and 41 are pivoted at their bowed ends by pin 42 and whose opposite ends are respectively provided with curved surfaces 43 and 44, respectively adapted to fit the outer 5 and the inner surface of each pair of turbine blades or vanes, as indicated in Fig. 1. Preferably intermediate the ends of said arms 40 and 41 is a screw 45 having an angular head 46 loosely fitting opening 47 in arm 40 and pivotally secured 10 therein by a pin 48 passing through said arm 40 and said head 46. One or more nuts 49 are threaded on screw 45 intermediate the arms 40 and 41. The free end of screw 45 is adapted to pass through a hole in the arm 41, in the 15 instance shown in Figs. 1 and 2, and has threaded thereon a nut 50. When the surfaces 43 and 44 of respective arms 40 and 41 are the requisite distance apart the nut 49 is adjusted to contact with the inner adjacent surface of 20 arm 41, and the other nut 49, which when employed functions as a lock-nut, locks the first mentioned nut 49 in said position, which position is maintained throughout the lacing of the row of blades or vanes.

With the surfaces 43 and 44 respectively of 25 arms 40 and 41 placed on opposite sides of a pair of blades or vanes, preferably in the relative position shown in Fig. 4, and initially on opposite sides of the ends of adjacent tubes 14, the nut 30 50 is tightened to clamp arm 41 firmly against its adjacent nut 49. This insures the uniform spacing of each pair of blades or vanes. The blades or vanes 11 are radial, and the fixed uniform distance therebetween in each row is at a 35 fixed point in their length. To readily preserve this fixed point while progressing along the row, each of the arms 40 and 41 is provided with a rod 60 passing through an opening therein and clamped thereto by a screw 61, one end of each 40 of said rods 60 is adapted to engage the base 45 ledge of the rotor or stator to hold the arms 40 and 41 at a point in the length of the blades or vanes 11 at which the distance therebetween will be uniform throughout the row. The jaws 22 and 23 of the bifurcated lacing tool indicated 50 in Figs. 5 and 6 are then placed on opposite sides of first one and then the other of the pair of blades or vanes, spaced and held by said portions 43, 44 adjacent ends of tubes 14. Said jaws 55 are then clamped together to flatten the tube between them, while said arms 40 and 41 prevent the adjacent turbine blades or vanes from being spread apart as a result of the flattening of the tubes between them. The spacing tool is then withdrawn and replaced on opposite sides of the next pair of blades or vanes, including the ad-

jacent one of the pair of blades or vanes previously spaced and secured. When such succeeding pair of blades or vanes are thus properly spaced the aforesaid jaws 22 and 23 are employed to flatten the tube 14 in a plane intermediate the spacing arms 40 and 41. This operation is repeated until all the blades or vanes in each row are thus securely laced together.

It will be appreciated by those skilled in the art that turbine blades and their lacing members may be made of such metal or alloy of greater efficiency than has been heretofore possible due to our invention dispensing with the requirement that rivet portions be formed on the outer or free ends of the blades or vanes and providing that the blades may be secured together of uniform spacing without strain of the blades or vanes in either their construction, assembly or replacement, and that more rigid blades or vanes result from our invention which are freer from variations due to temperature changes.

The herein described invention may be manufactured and used by or for the Government of the United States for governmental purposes without the payment of any royalties thereon or therefor to any or all of the undersigned inventors.

Having thus set forth and disclosed the nature of this invention, what is claimed is:

1. In a tool for holding in spaced relation unsecured portions of turbine blades, a pair of relatively movable pivoted arms adapted to engage opposite surfaces of adjacent blades, means carried by the arms for removably maintaining them at a predetermined spaced relationship, and rods to contact either the turbine rotor or stator adjustably mounted on the tool to evenly position it on the blades as it is progressively moved around the turbine.

2. In a tool for holding in spaced relation unsecured portions of turbine blades, a pair of relatively movable pivoted arms adapted to engage opposite surfaces of adjacent blades, means carried by the arms for removably maintaining them at a predetermined spaced relationship, and rods relatively adjustably carried by each of the arms for resting upon the blade support to compensate for curvature in the blade support whereby the tool is positioned at a uniform distance from the support as it is progressively moved around the turbine.
